Fig. 3

Fig. 4

Fig. 5

Fig. 6

FIGURE 1 is a side elevational view of a tool for lifting reams of paper showing my new design, the side opposite being a mirror image thereof;

FIGURE 2 is a top plan view thereof;

FIGURE 3 is a bottom plan view thereof;

FIGURE 4 is an end elevational view, the end opposite being a mirror image thereof;

FIGURE 5 is a sectional view taken along line 5—5 of FIGURE 1; and

FIGURE 6 is a sectional view taken along line 6—6 of FIGURE 1.

I claim:

The ornamental design for a tool for lifting reams of paper, as shown and described.
